Primary Examiner — Kelley A Donnelly

(74) Attorney, Agent, or Firm — Koenig IP Works, PLLC;
Katherine Koenig(57) **CLAIM**

The ornamental design for modular shelving component, as shown and described.

DESCRIPTION

FIG. 1 is a top rear perspective view of a modular shelving component;

FIG. 2 is a front view thereof;

FIG. 3 is a rear view thereof;

FIG. 4 is a left side view thereof;

FIG. 5 is a right side thereof;

FIG. 6 is a top view thereof;

FIG. 7 is a bottom view thereof; and,

FIG. 8 is a top front perspective view thereof.

Any broken line illustration of environmental structure in the drawings is not part of the claimed design.
